UNITED STATES PATENT OFFICE.

SEYMOUR W. PEREGRINE, OF MINNEAPOLIS, MINNESOTA.

SCHOOL SEAT AND DESK.

SPECIFICATION forming part of Letters Patent No. 326,774, dated September 22, 1885.

Application filed January 14, 1885. (No model.)

To all whom it may concern:

Be it known that I, SEYMOUR W. PEREGRINE, of Minneapolis, in the county of Hennepin and State of Minnesota, have invented 5 new and useful Improvements in School Seats and Desks: and I do hereby declare that the following is a full, clear, and exact description thereof, reference being had to the accompanying drawings, which form a part of 10 this specification.

This invention relates to new and useful improvements in school desks and seats, and seats for opera-chairs and for public halls.

The invention consists in the peculiar arrangement and construction of the parts, all 15 as more fully hereinafter set forth.

It is a well-known fact that the most suitable position a scholar should assume at his desk for writing is not a suitable position for 20 him to read in; but with stationary or partly-adjustable desks as they are in present use there is but little chance for the scholar to assume different positions, however necessary it is both for his health and comfort. Such adjustability of desk which only permits of varying 25 its incline is insufficient, as it does not change the focal distance enough to relieve the eye of the scholar from that weariness produced by continued use of the eye without 30 materially changing its focus, and which is so productive of short-sightedness.

My invention produces a desk which is not only adjustable as to its incline, but which is also adjustable in its height to a much larger 35 degree than is obtained by a mere changing of its incline around stationary hinges. In combination with such adjustability I have arranged a contrivance by means of which the scholar can instantly, by a simple turning of 40 a hand-lever, effect any desired adjustment without moving from his seat.

A further object of my invention is to improve the construction of the stop for the folding seat and of the hinges, by means of which 45 the folding seat and the cover of the desk are secured. These parts are generally troublesome and need the special attention of the manufacturer. I have devised new constructions by means of which they will prove more 50 suitable in their different functions.

My invention also includes an improved con-

struction of devices used for securing the wooden slats of the seat and its back to the iron frame.

In the drawings which accompany this 55 specification, Figure 1 is a perspective view of my improved school desk and seat. Fig. 2 is a sectional front elevation, the parts in section being shown on a plane which passes through the hinges and stops of the folding 60 seat. Fig. 3 is a perspective view of the desk and the upper portions of the standards, both detached from each other. Fig. 4 is a detached perspective view of the device for securing the wooden slats to the iron frame. 65 Fig. 5 is a plan of the desk, showing the arrangement of the desk-hinge. Fig. 6 is a cross-section of the desk-hinge on line x x in Fig. 5. Fig. 7 is an elevation of the desk-hinge. Fig. 8 is a modification of the seat-hinge 70 shown in Fig. 2.

A A are the iron standards which form the supporting-frame of the school desk and seat. B is the folding seat. C is the wooden back of the seat, and D is the desk, all these parts 75 being of well-known construction and arrangement except as hereinafter specified.

The seat consists of a series of wooden slats secured edge to edge upon the top rail of the two iron brackets D' D'. These brackets are 80 pivotally secured upon their lower ends to the standards A, so as to form a hinge, E, for folding the seat backward, a stop or buffer, F, operating in connection therewith to limit the forward and backward motion of the seat in 85 folding and unfolding.

The construction of the hinges E is as follows: a is a taper bushing of Babbitt or other soft composition. It has a flange, b, on one end, and has a bolt, c, passing through it and 90 the standard A. The lower end of the bracket D' has a taper socket formed in it, which fits the taper of the bushing, and a suitable nut and washer upon the inner end of the bolt hold the parts in position and form the 95 means for tightening the joint. With this construction of the hinge all lost motion can be taken up and the most suitable stiffness of joint obtained and maintained without any further attention than an occasional tightening of the screw-nut. 100

In Fig. 8 I show a detached section of a

modification of the seat-hinge just described, and which works upon the same principle; but instead of journaling the seat-bracket upon the taper bushing, the taper bushing forms, so to speak, a part of the seat-bracket, and is journaled into the iron standard.

The buffer F, which works in connection with the iron brackets of the hinged seat to arrest it in the proper position to sit on, and 10 also to prevent its being folded too far back, is constructed as follows: d d are two bushings provided with flanges upon their outer ends. e is a rubber ring fitting upon the hubs of the bushing, and f is a bolt passing through 15 the standard and provided with a suitable nut, by means of which the rubber ring is firmly compressed between the flanges of the bushings, and whereby the whole buffer is firmly secured to the standard. The inner 20 ends of the bushings are so shaped that one projects within the other, so as to lock upon each other and resist lateral displacement, as shown in the drawings, where the end of one bushing is shown convex and the other concave. 25

A buffer thus constructed operates noiselessly without being too yielding. It is very firm, owing to the interlocking of the two bushings. Its rubber ring is firmly compacted, 30 and it has the further advantage that the deterioration of the rubber ring does not affect its rigidity.

The slats of the seat and of the back are secured to their standards or supports in a novel 35 manner, (shown in Figs. 2 and 4 of the drawings,) in which G is an iron pin, cast or otherwise secured to the standard A and to the top rails of the seat-brackets. These pins project just the thickness of the slats. They have an 40 oval-shaped head formed upon their free ends, and beneath this head the pin has a contracted neck, so as to form two partial screw-threads, g g, upon the two most eccentric parts of the head. H is a round nut with an opening 45 through it large enough to allow the nut to be slipped over the head. Upon two opposite sides of this opening two partial screw-threads, h h, are formed, similar to the screw-threads upon the heads of the pin. Holes are bored 50 through the slats to receive the pins, and suitable countersinks are made to receive the nuts, with rubber or paper washers at the bottom, so as to bring them flush or nearly so with the face of the slat. After a nut is slipped over 55 the head of a pin, a quarter of a turn is given to the nut, which, for that purpose, has a groove across its face to be operated by a wrench. This turning of the nut engages its screw-threads underneath the screw-threads 60 of the head, and firmly presses the slat against its support. The rubber or paper washers prevent the nuts from working loose. The head of the pin is preferably provided with a little boss, i, and a corresponding notch, j, 65 is formed in the nut, which, when the latter is properly tightened, locks with the little boss

i. In addition to this means for securing the slats in position upon their supports, the slats are provided with dowels upon their adjoining edges, or any other known device for securing the edges of the slats together may be used. 70

The desk D is of the usual form; but its lid is hinged to the ink-well board by an improved strap-hinge constructed as follows: I is the stationary part of the hinge, and J the movable part. The latter is secured by screws to the under side of the lid outside of the desk-frame, and is of proper shape and length to prevent the lid from warping. The stationary part of the hinge is secured to the inside of the desk-frame, as shown in Figs. 5 and 6, by means of suitable screws or rivets, k. The inner ends of the straps of the hinges turn upwardly, with an eye formed on each, through 75 which the rivet passes to hold the hinge-joints together. The eyes of the hinges have bosses l formed upon their inner faces to bring the two straps the necessary distance apart to allow the lid-strap to come outside the desk-frame 80 and the other strap to come inside the same. One of the bosses l has a shoulder formed upon it, and the other is formed cup-shaped and journaled upon this shoulder, so as to take the strain off from the rivet, which latter merely 85 holds the joint together. The hinge-joint is entirely concealed within the lid, with the pivotal point in the central plane of the lid, and the joint between the ink-well board and the lid concentric to this pivotal point. By this 90 arrangement no weak edges are formed on the joints between these boards, and no liability exists of wedging anything between them. 95

To each side of the desk are secured two pins, o p, which project outwardly therefrom, 100 and which engage into slots or grooves m n, formed in the upper part of each standard. In Fig. 1 the pins o p rest upon the bottom of their respective slots, and thereby hold the desk firmly in a position which is calculated 105 to be the lowest for practical use in writing. To raise the desk vertically and lock it in position at varying heights, I have contrived the following simple arrangement: r is a shaft journaled in the standards below the desk. 110 s is a handle for turning the shaft. t is a semi-circle provided with a series of notches, u, for locking the handle, which is made of spring-metal, in position to engage into one of the notches. v are two slotted or grooved cams 115 secured upon the shaft r, and w w are two pins projecting inwardly from the lower ends of the frames of the desk. The pins w engage 120 into the grooves or slots v' of the cams v, and by turning the handle s the desk can be adjusted vertically. The throw of the cams is made sufficient to raise the desk by half a turn of the handle from its lowest position to its highest position, the pins o p being compelled to travel in the slots m n, and give the 125 desk the inclination which results from the relative inclination of the two slots. As the 130

desk in its higher positions is the most suitable for reading, the slots *m n* are given such a relative inclination to each other that simultaneously with the raising of the desk into its higher positions it changes gradually from the level which it assumes in its lowest positions to an incline in the highest position. Thus the desk at its different heights is also made to alter its incline in the manner most suitable for the work at which the different heights of the desk ought to be used.

In the drawings it will be observed that the slot *n*, beginning from its lowest point, assumes gradually a rearward sweep toward its upper end, while the upper slot, *m*, is straight and nearly vertical. This relative arrangement of the two slots produces the desired change of inclination at the different heights of the desk.

20 To enable the desk to be removed from the standards, the upper slot, *m*, is left open at the top, and the lower slot, *n*, is provided with an exit-groove, *n'*, through which the pin *p* may be passed out. To remove the desk, the lever *s* is turned until it engages into the notch *u'*, which brings the pins *p* to the exit-slots *n'*, and turns the cams *v* into such a position that the pins *w*, which engage into these cams, may be also disengaged from the cam-slots. By 30 tipping the desk now upwardly the pins *p w* will easily disengage from their respective slots and the desk can be removed.

The semicircle *t* is provided with several notches, to lock the lever *s* in different intermediate positions between the highest and lowest, so as to suit the requirements of scholars of various ages, and to make the adjusting devices work noiselessly I cushion the notches with rubber, and also provide rubber cushions 40 for the closed ends of the slots *m n*, against which the pins *o p* are intended to rest at the lowest or highest adjustments of the desk. The latter rubber cushions I preferably construct by forming a half-circular enlargement in the 45 end of the slot, and inserting therein a rubber plate of proper size to form a half-circular cushion. By such an arrangement the natural tendency of the rubber keeps it firmly in place without the aid of other devices.

50 The spirit of my invention in the adjustable desk consists in providing the standards with guide-slots or grooves and the desk with guide-pins, or vice versa, in combination therewith devices for holding the desk in position at different heights. Various devices may be adopted for this purpose, such as providing the main guide-slots *m n* with little pockets or offsets at different heights, into which the pins *o p* may be engaged. In the practical application of 55 my invention, however, it will be considered a great advantage to combine the vertical adjusting devices with a mechanically-operating device for effecting any desired adjustment instantly, noiselessly, and simply by turning a handle convenient to the hand of the scholar 60 while sitting at his desk, a device which can

be safely and easily operated by the merest child.

A further advantage gained by the use of my adjustable desk is that the unsymmetrical 70 appearance of the school-rooms arising from the use of school-desks of various sizes to suit scholars of different ages and body development is greatly done away with, as in addition to the vertical adjustment of the desk I provide the standards with adjusting-holes *z* for the hinge of the seat, so as to adjust the seat 75 higher or lower, as required for the comfort of the scholar.

To prevent spilling of the ink while adjusting or removing it, I preferably use an ink-well which fastens to the back.

I deem it important that the bushing *a* be of soft metal and of taper form, as such material avoids creaking and allows the loss by 85 wear to be readily taken up.

What I claim as my invention is—

1. In a folding seat, the hinge *E*, provided with the flanged taper bushing *a*, of soft composition metal, which forms the pivot of the 90 hinge, and the bolt *c*, provided with nut and washer to tighten the hinge and secure it to the standard, substantially as described.

2. In a folding seat, the buffer *F*, consisting of the rubber ring *e*, of the bushings *d*, having 95 compression-flanges for the rubber ring and interlocking meeting-faces, and of the bolt *f* and its nut, all combined substantially as described.

3. In a school desk and seat, the devices for 100 securing the slats of the seat and back, consisting of the pins *G*, secured to the frame and provided with partial screw-threads formed by undercutting their heads, and of the round compressing-nuts, also provided with partial 105 screw-threads and adapted to be slipped over the head of the pin and secured thereupon by a quarter-turn, all arranged substantially as described.

4. In a school desk and seat, a seat-fastening 110 device consisting of a round pin, *G*, provided with interrupted single screw-threads upon its head formed by cutting away the body of the pin, of a round nut provided with similar interrupted single screw-threads and adapted to 115 be slipped over the head of the pin and secured thereupon by a quarter-turn, and of the boss *i* and notch *j* for locking the nut in position, all arranged substantially as described.

5. In a school-desk, a lid-hinge with its pivotal point located in the central plane of the lid and the joint between the ink-well board and lid concentric thereto, said lid-hinge consisting of the straps *I J*, turned upwardly at their inner ends and provided with bosses *l* 120 upon their eyes, which admit of securing the stationary part of the hinge inside of the desk-frame and the movable part outside, said bosses forming a cup-joint secured together by a rivet, all constructed substantially as described.

6. In an adjustable school-desk, adjusting

devices for changing the height and inclination of the desk, the same consisting of guide slots or grooves of relative different inclines in the standards and guide-pins upon the 5 sides of the desk engaging into these slots or grooves, or vice versa, in combination with devices for holding the desk in its adjusted position, substantially as set forth.

7. In an adjustable school-desk, and in combination with the guide-slots and guide-pins of the desk, a mechanically-operating device for adjusting the desk, consisting of the rock shaft *r*, grooved cams *v*, pins *w*, handle *s*, and notched quadrant or semicircle *t*, or other 15 equivalent device.

8. In an adjustable school-desk, and in combination with the guide-slots *m n* and guide-pins *o p* and the mechanically-operating adjusting device, the spring-handle *s*, arranged 20 upon the side of one standard within reach of the scholar from his seat, and the notched semicircle or quadrant *t*, substantially as described.

9. In an adjustable school-desk, and in combination with the guide-pins *o p* upon the side 25 of the desk engaging into the guide slots or grooves in the standards, the slots *n*, provided with the exit-slots *n'*, and the slots *m*, open at

the top, substantially as and for the purposes described.

10. In an adjustable school-desk, in combination with the guide-pins *o p* upon the side of the desk, the slots *n*, provided with exit-slots *n'*, the slots *m*, open at the top, and the open cam-grooves *v'*, into which the adjusting-pins *w* engage, substantially as and for the 30 purposes described. 35

11. In an adjustable school-desk, the combination of the guide-pins *o p*, adjusting-pins *w*, guide-slots *m*, open at top, guide-slots *n*, having exit *n'*, and open cam-grooves *v'*, with the notch *u'* of the adjusting device so arranged as to fix the point of exit for the simultaneous withdrawal of the pins *p* and *w*, substantially as described. 40 45

12. In an adjustable school-desk, the combination of the guide-pins *o p*, upon the sides of the desk, of the guide-slots *m n* in the standards, and of rubber cushions arranged in the ends of the guide-slots and formed by rubber plates fitted into half-circular enlargements in the ends of the slots, substantially as described. 50
